(57) **CLAIM**

The ornamental design for a fish tape handle, as shown and described.

DESCRIPTION

FIG. 1 is a front perspective view of a fish tape handle according to our new design;

FIG. 2 is a left side elevational view thereof, the right side elevational view being essentially a mirror image thereof;

FIG. 3 is a front elevational view thereof;

FIG. 4 is a back elevational view thereof;

FIG. 5 is a top plan view thereof; and,

FIG. 6 is a bottom plan view thereof.

The broken line showing is for illustrative purposes only and forms no part of the claimed design.
